ATTORNEYS

UNITED STATES PATENT OFFICE.

ADOLPH THOMMEN, OF NEWARK, NEW JERSEY, ASSIGNOR OF ONE-HALF
TO ENOS RICHARDSON & CO., OF SAME PLACE.

DESIGN FOR A POSTAGE-STAMP BOX.

SPECIFICATION forming part of Design No. 19,925, dated June 24, 1890.

Application filed May 2, 1890. Serial No. 350,385. Term of patent 7 years.

To all whom it may concern:

Be it known that I, ADOLPH THOMMEN, a citizen of the United States, residing at Newark, in the county of Essex and State of New Jersey, have invented and produced a new and original Design for a Postage-Stamp Box, of which the following is a specification, reference being had to the accompanying drawings, forming part thereof.

Figure 1 is a front view of a postage-stamp box showing my design. Fig. 2 is a back view of the same, and Fig. 3 a perspective view of the same, these three views being deemed necessary to fully illustrate my de-

sign.

The leading feature of my design consists in a box having on its front face an address, a representation of a postage-stamp and post-office mark, and on its back an imitation of a post-office date-mark.

A is the box, which is rectangular in its

general contour, is slightly rounded at the parts *a*, has the lines *a'* connecting the front and back of the parts *a*, has an address *b* written across its face, a figure *c* made as a miniature representation of a postage-stamp, and a figure *d*, representing a post-office mark, being shown near upper right-hand corner on the front face of the box, and which has upon its back the centrally-converging lines *e*, extending from the parts *a* to the center and made to simulate the flaps of an envelope, giving to the part *e'* the appearance of overlapping the part *e*, and the figure *f* made to represent the date-mark of a post-office. 35

I claim—

The design for a postage-stamp box herein shown and described.

ADOLPH THOMMEN.
